UNITED STATES PATENT OFFICE.

WILLIAM THURBER AND ANDRUS NORLING, OF CHICAGO, ILLINOIS.

HORSE-COLLAR.

SPECIFICATION forming part of Letters Patent No. 372,439, dated November 1, 1887.

Application filed February 24, 1887. Serial No. 218,653. (No model.)

To all whom it may concern:

Be it known that we, WILLIAM THURBER and ANDRUS NORLING, of Chicago, county of Cook, and State of Illinois, have invented certain new and useful Improvements in Horse-Collars, of which the following is a full, clear, and exact description, that will enable others to make and use the same, reference being had to the accompanying drawings, forming a part 10 of this specification.

The object of this invention is to provide an improved collar which will combine cheapness and durability, together with convenience in adjustment, the same consisting of certain 15 novel features in the construction, arrangement, and operation of the several parts, as will be hereinafter set forth in detail.

Figure 1 is a front elevation of a collar embodying our improved features. Fig. 2 is an enlarged transverse section in the plane 2, Fig. 1, showing the opposite side; Fig. 3, a detached view of one of the hame-irons, showing the side that is outward from the collar; Fig. 4, a detail of one side of the neck-yoke broken away; 25 Fig. 5, a horizontal transverse section of the joining ends of the neck-yoke; Fig. 6, a detached detail of construction, and Fig. 7 a modification.

In the drawings, A A represent the two 30 pads forming the collar proper, which will be composed of paper or wood pulp molded in the desired form. The pads are provided with the scores *a* to form a yielding joint. The opposite or bearing sides of the collar-pads are 35 provided with the flexible metallic plates *a'*, (see Fig. 2,) which extend above and below the scored parts. These plates will be usually of thin sheet-steel or other suitable metal combining the required strength and flexibility, 40 and will be embedded flush with the surface of the pads, so as to present a smooth bearing.

Instead of having the pads scored, they may be in a number of parts and hinged together by the metallic plates, the object of this construction being to provide the pads with a flexible joint, whereby the collar will automatically 45 adjust itself to a uniform bearing, no matter how full or round the shoulders and breast of the horse may be.

50 The steel backing-plates may in some cases be dispensed with and the pads provided with

one or more scores at the point where the greatest flexibility is required. Dispensing with the metal plates will, however, depend somewhat on the nature of the material composing the collar-pads. The permanently secured hame-irons will cover and strengthen the scored parts, and when the collar is composed of wood, and in two or more parts, the hame-irons will retain said parts in proper relation 55 to each other in the absence of backing-plates.

The hame-irons B B form a permanent part of the collar, and may be secured thereto in any suitable manner. These hame-irons are provided with the outwardly-projecting pivot-post *a'*, terminating in the small pin or pintle *a''*. The neck-yoke connecting the lower parts of the collar-pads is composed of two pieces, C C, which are of a curved angular form, the lower parts being curved to conform to the 70 contour of the breast or neck of the animal, while the upper ends are bent outwardly and project at right angles for the attachment of the hame-tug. The convex bearing surface of the pivot post or posts *a'*, forming an integral 75 part of the hame-irons, engages with the concavity or depression *a'*, (see Fig. 6,) situated in the angle or corner of the neck-yoke pieces. The pin prolongation *a''* on the pivot-posts passes through the small apertures *b*, which 80 are a continuation of the concave depressions in the neck-yoke. This form of construction loosely unites these parts, and at the same time prevents them from becoming disengaged under ordinary circumstances. The pivotal arrangement of the hame-irons and neck-yoke 85 adapts these parts to have an automatic adjustment, and also an action similar to that of a universal bearing or joint, thereby enabling the collar to readily conform to the movements 90 of the horse, which require both a lateral and a rolling adjustment.

The lower or joining ends of the neck-yoke overlap, and have a sliding endwise adjustment relative to each other, and are provided 95 with perforations *b'*, which coincide for the insertion of a suitable locking-pin when adjusting the yoke to fit necks of different sizes, and thus enabling the collar to be conveniently fitted to any animal. The adjusting ends are 100 retained in proper position relative to each other by means of the adjusting clip or clasp D.

In the process of making the collar-pads from paper or wood pulp, the flexible metallic plates and the hame-irons may be placed in the mold or former, and in that manner permanently secured to the collar. These parts may also be attached in any other suitable manner.

The particular form of construction and arrangement of the different parts forming the collar proper adapts the same to quickly adjust itself to the movements of the horse, and at the same time retain its proper position and bearing on the muscular parts of the neck and shoulders, the universal action equalizing the draft-strains and preventing the load from being alternately shifted from one shoulder to the other as the horse moves forward.

As the parts yield readily with each step, the horse is enabled to draw a heavy load with ease, for the reason that the collar has an equal bearing or pressure along the whole line of draft, which is not the case with the ordinary collar, wherein the load is alternately transferred from shoulder to shoulder with every step. The collar-pads, being made of paper, are very light, and will retain their original shape under all circumstances. A hard smooth bearing-surface is presented which will not wrinkle to chafe or gall the animal. The space left between the lower ends of the collar and bridged over by the neck-yoke prevents any pressure on the wind-pipe or any interference with a free respiration.

The pads forming the collar proper may be made of any suitable material other than paper-pulp without departing from the spirit of our invention.

Fig. 7 is a modification showing a slight change in the construction of a hame-iron, and also a different joint for connecting the hames with the neck-yoke.

Having thus described our invention, what we claim as new, and desire to secure by Letters Patent, is—

1. A horse-collar the pads wherof, forming the collar proper, are provided with one or more scores, as at *a*, to form a flexible yielding joint, whereby the pads will automatically adjust themselves to a uniform bearing on the

breast and shoulders of the animal, substantially as set forth.

2. A horse-collar the pads wherof, forming the collar proper, are scored and provided with flexible metallic backing-plates, substantially as and for the purpose set forth. 55

3. In a horse-collar, the combination, with the pads thereof provided with scores, as at *a*, to form a flexible joint, of the hame-irons *B B*, permanently secured thereto and covering the 60 scored parts, substantially as set forth.

4. In a horse-collar, the combination, with the collar-pads provided with one or more scores, as at *a*, of the metal backing plate or plates secured to the inner or bearing surface 65 of said pads, and the hame-irons permanently secured to the outer side, substantially as set forth.

5. In a horse-collar, the combination, with the hame-irons provided with the pivot-post 70 *a*², having a convex bearing-surface and terminating in the pin *a*³, of the neck-yoke having a corresponding concavity and aperture, whereby said parts are automatically adjustable relative to each other, substantially as and 75 for the purpose set forth.

6. In a horse-collar, the neck-yoke pieces *C C*, having the upper ends turned outwardly at right angles for the attachment of the hame-tugs, while the lower parts follow the contour 80 of the collar-pads, curving inwardly in the direction of and overlapping each other, and the means described for adjusting said overlapping ends, whereby the space between the lower ends of the collar-pads may be widened 85 or narrowed, as may be required, substantially as set forth.

7. In a horse collar, the combination, with the pads composing the collar proper, of the hame-irons *B B*, permanently secured to said 90 pads, and the adjustable neck-yoke parts *C C*, loosely attached to said hame-irons and having an automatic adjustment relative thereto, substantially as and for the purpose set forth.
